CLAIM

The ornamental design for a rotary scrub pad, as shown and described.

DESCRIPTION

FIG. 1 is a top plan view of a first embodiment of a rotary scrub pad, the bottom plan view being identical to that shown.

FIG. 2 is a side elevational view thereof, the opposite side being identical to that shown.

FIG. 3 is a top perspective view thereof, the bottom perspective view being identical to that shown.

FIG. 4 is a top plan view of a second embodiment of a rotary scrub pad the bottom plan view being identical to that shown.

FIG. 5 is a side elevational view of the second embodiment of a rotary scrub pad the opposite side being identical to that shown; and,

FIG. 6 is a top perspective view of the second embodiment of a rotary scrub pad the bottom perspective view being identical to that shown.
